CLAIM

The ornamental design for a gripping accessory for a mobile computing device, as shown and described.

DESCRIPTION

FIG. 1 is a top, front isometric view depicting a gripping accessory for a mobile computing device;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a lower bottom, rear isometric view thereof.

The broken lines in the drawings depict portions of the article that form no part of the claimed design.
